LIGHTING UNIT

Filed Feb. 28, 1925.

Inventor:
Cromwell A. B. Halvorson, Jr.
by *Alexander F. Lunt*
His Attorney.

UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHTING UNIT.

Application filed February 28, 1925. Serial No. 12,425.

My invention relates to lighting units. More particularly the invention relates to lighting units which are especially adapted for highway lighting or for flood lighting.

5 Ordinarily highway lighting units are not used for flood lighting purposes but it is one of the objects of my invention, however, to provide means whereby such units may serve for flood lighting purposes. In the unit of 10 my invention I contemplate the use of two sources of light: one a high power source for use during the early hours of the evening and for supplying light to a flood lighting reflector; the other a low power 15 light source for use during the late hours of the night. The unit of this construction has a general light distribution and a special reflector located between the light sources which serves to concentrate light 20 upon one particular area for flood lighting purposes.

The details of the unit are hereinafter more fully set forth and claimed, reference being had to accompanying drawing, in 25 which the figure shows the lighting unit of my invention in elevation and partly in section.

Referring more in detail to the drawing it will be seen that the unit comprises an 30 enclosing globe 2 in which the light sources 3 and 4 are located. These light sources are connected in any suitable manner with the source of current for producing the necessary light with suitable switches whereby 35 the lights may be turned on and off, either one at a time or simultaneously. For example, in the early hours of the evening it may be desirable to turn on the upper light source 4 alone or both the light sources at 40 the same time and after a given hour, midnight for example, the upper light may be turned off, the lower alone serving as the source of light for the remainder of the night. In the preferred form of construction 45 I provide a main reflector 5 above the light source 4, which reflector may preferably be in the form of an ellipsoidal reflector. In this combination the center of the light source will be located at the focal 50 point F of the ellipsoid nearest the reflector, while the second focal point F' may be arranged to fall at a point between the two light sources as indicated in the drawing. In the preferred form of construction 55 I contemplate the use of a paraboloidal re-

flector 6, the focal point of which coincides with the focal point F, of the ellipsoid. However the reflector 6 may be of any other suitable form or type, for example, it may be in the form of a plane surface or of any 60 suitable curved surface. It may also be corrugated or perforated to allow some light to pass to the rear. As indicated the reflector 6 may be secured to the upright 7, to the upper end of which the socket for the light 65 source 4 is attached. The globe 2 as shown rests on a base element 8, which in turn is secured to the upper end of a stand or post 9. Within the base 8 there is provided a framework 10, to which the socket for the 70 light sources 3 may be attached. Resting on the upper part of the globe there is a suitable hood 11, which may be secured to the globe by means of series of screws 12.

It will be seen therefore that with a construction such as described and illustrated a highway lighting unit of attractive design and having a general light distribution may be used to secure also and at the same time a flood lighting beam without much additional expense, without detracting from the appearance and without at the same time producing objectionable shadows which might destroy the artistic effect of the unit. 75

In the figure the axis $\alpha-\alpha$ of the paraboloidal reflector 6 is shown inclined to the axis of the main reflector 5. With such a reflector the rays that pass through the focal point F will be projected by the reflector 6 to the right parallel to the axis $\alpha-\alpha$ while 80 the other rays that strike the reflector 6 will be projected in different directions. The result therefore is an asymmetric distribution. When a plane glass reflector is used the reflected rays of the diverging beam will not be parallel as is the case when a paraboloidal reflector 6 is used but there will be asymmetric distribution with an intensified section produced by the plane reflector. 85

While I have shown and described my invention in a specific and concrete form it will be understood I do not wish to be so limited inasmuch as variation and modification of my invention will readily suggest themselves in view of the disclosure and may be produced without departing from the spirit of the invention or from the scope 90 of the claim herein.

What I claim as new and desire to secure 100 by Letters Patent of the United States is:— 110

In a lighting unit, an ellipsoidal reflector and a pair of light sources located along the axis of the reflector, an auxiliary concave reflector located across said axis, one of said light sources being located at one of the focal regions of the ellipsoidal reflector, said auxiliary reflector having a focal region coincident with another focal region of the ellipsoidal reflector, said ellipsoidal reflector serving to produce a beam along the axis of the unit and the auxiliary reflector serving to produce a beam diverging from the axis of the unit.

In witness whereof, I have hereunto set my hand this 26th day of February, 1925.

CROMWELL A. B. HALVORSON, Jr.
